UNITED STATES PATENT OFFICE.

OTTO LUDVIG SAMUELSON, OF CHICAGO, ILLINOIS.

EXERCISING APPARATUS.

1,386,206.

Specification of Letters Patent.

Patented Aug. 2, 1921.

Application filed May 26, 1919. Serial No. 299,915.

To all whom it may concern:

Be it known that I, OTTO LUDVIG SAMUELSON, a citizen of the United States, residing at Chicago, in the county of Cook and State 5 of Illinois, have invented certain new and useful Improvements in Exercising Apparatus, of which the following is a specification.

This invention relates to improvements in 10 exercising apparatus and its object is to provide mechanical means such as will enable a person to take light or heavy exercise, the device being adjustable to suit persons of more or less strength. A further 15 object is to provide exercising apparatus that will be conducive to deep breathing. With the foregoing and other objects in view the invention consists in the combination and arrangement of parts to be herein- 20 after fully described, pointed out in the appended claim and illustrated in the accompanying drawing which forms a part of this specification and in which—

Figure 1 is a view of my invention in 25 front elevation.

Fig. 2 is a side view of Fig. 1.

Figs. 3 and 4 are enlarged fragmentary views illustrating the tension apparatus.

Like reference characters denote corre- 30 sponding parts throughout the several views.

My exercising apparatus comprises the inverted U-shaped side pieces 1, 2 connected by the braces 3 and carrying the frame 4 35 likewise of inverted U-shaped formation. Upon the said side pieces 1, 2 the rotary crank shaft 5 is arranged provided with the pedals 6, one end of said crank shaft being projected beyond the side pieces 1 and pro- 40 vided with the sprocket wheel 7 that is connected by sprocket chain 8 to another sprocket wheel 9 fast upon one end of a second crank shaft 10 which shaft is jour- 45 naled in bearings 11 secured to the frame 4, said crank shaft 10 being provided with the hand grips 12, the supports of said shaft 10 being arranged upon the opposite side of the frame 4 with relation to the bearings of shaft 5 so that the operator in using the 50 device will stand in an upright and natural position which will be conducive to deep breathing thus affording the maximum

beneficial effect from the use of the device. The chain 8 connecting the shafts 5, 10 causes uniform movement of the same. 55

To one end of the shaft 10 a grooved wheel 13 is made fast and a belt 14 engages the same, one end of said belt being secured to a gage bracket 15 secured to one side of the frame 4 and the other end being secured to 60 a contractile spring 16 connected to a tension screw 17 which extends through a perforation in the lower end of the gage bracket and is provided with the adjusting nut 18 whereby it may be raised or lowered 65 with relation to said bracket, said tension screw carrying an indicator 19 that operates in the elongated slot 20 of said gage bracket and passes over the graduations 21, in pounds, marked upon said bracket. By ad- 70 justing the screw 17 downwardly rotation of the wheel 13 and shaft 10 is frictionally retarded thus making the operation of the device more difficult and calling forth greater strength on the part of the operator 75 thus gradually developing his muscular power.

What is claimed is:—

In an exercising apparatus, connected frame supports, an upright frame carried 80 thereby, a crank shaft arranged upon said frame supports and spaced away from said frame, one end of said crank shaft being extended beyond the adjacent side of the frame, pedals for said crank shaft, a second 85 crank shaft carried by said frame and disposed upon the opposite side thereof with relation to the said first crank shaft, the ends of said second crank shaft being ex- 90 tended beyond the sides of the frame, chain connection between the extended ends of said crank shafts at one side of said frame, means connecting said frame and an ex- 95 tended end of said second crank shaft at the opposite side of said frame for friction- ally retarding rotation of the latter shaft, and an indicator associated with said means.

In testimony that I claim the foregoing as my own I have hereto affixed my signature in the presence of two subscribing witnesses. 100

OTTO LUDVIG SAMUELSON.
